UNITED STATES PATENT OFFICE.

JOHN E. McLEOD AND ARTHUR J. HEWITT, OF WASHINGTON, KANSAS.

DRAFT REGULATOR.

Application filed January 17, 1923. Serial No. 613,184.

To all whom it may concern:

Be it known that we, JOHN E. McLEOD and ARTHUR J. HEWITT, citizens of the United States, residing at Washington, in the county of Washington and State of Kansas, have invented certain new and useful Improvements in Draft Regulators, of which the following is a specification.

Our invention relates to draft-regulating devices and is intended more particularly for use in connection with brooders for poultry to control the temperature therein.

In the accompanying drawings, one embodiment of the invention is illustrated and:

Figure 1 is a vertical sectional view of a brooder with our invention installed,

Figure 2 is a fragmentary side elevation in larger scale of the draft-regulating device,

Figure 3 is a perspective view of the smoke damper of the furnace,

Figure 4 is a perspective view of the details of the damper, and

Figure 5 is a side elevation of one of the implements used in connection with the furnace.

Referring particularly to Figure 1 of the drawings, the reference numeral 10 represents a chicken house or brooder with a floor 11 consisting of a thick layer of sand or gravel. The reference numeral 12 represents a furnace which is here shown in the shape of an inverted conic frustum built of masonry and sunk to about three-fourths 35 of its height into the ground. The top and bottom of the furnace are open and the top edge of the masonry is covered by a cast-iron ring 13 having a depending lip 14 engaging around the inner edge of the furnace 40 and an upwardly directed annular flange 114 adapted to engage with a corresponding flange 15 on the cover or lid 16. By this arrangement, the top opening of the furnace is entirely closed.

At the bottom of the furnace, where it is considerably smaller in diameter than at the top, a grate 17 is located. Around the top edge of the grate is a rim 9 about three-fourths of an inch in height, intended to 50 keep the coal from blowing off when the grate is removed. Below the grate is arranged an ash pit 18 with an ash pan 19 practically filling the pit. The ash pan is provided with handles 20 so that it may be 55 lifted out of the furnace by means of a hook 21 (see Figure 5) especially provided for

this purpose, after the lid 16 and the grate 17 have been removed. The grate 17 may also be lifted out by the same hook 21.

At one side of the furnace, about midway between the grate and the lid, we provide a damper consisting of a slidable door 22 covering the opening of a manifold 23 communicating with the furnace. As best seen in Figures 3 and 4, this manifold is constructed of an upper plate 24 and a lower plate 25 having interengaging flanged sides and back providing tubular outlets 26 adapted to engage the flue pipes 27, of which there are preferably two in the manifold. It will here be noted that the flanged sides of the plates will prevent warping of the manifold. The forward side of the manifold is curved to conform to the contour of the furnace into which it opens and the damper 22 is similarly curved and preferably provided with reinforcing ribs 28 and a hinge 29 located at the top edge of the damper and in the middle thereof. To this hinge is pivoted a two-arm lever 129 fulcrumed at 30 in the housing 31 connected with the manifold in any suitable manner such, for instance, as by means of a U-bolt 32. This housing consists of two inter-engaging plates 33 and 34 and is closed at its rear end by means of an angular bracket 35 provided with a perpendicular pipe 36 forming a guide for the operating rod 37 which is hinged to the inner end of the lever 129 as at 38. The plates 33 and 34 of the housing and the top plate 24 of the manifold, as well as the end bracket 35, are provided with interengaging lugs 136 to form a rigid construction. At the upper end of the pipe 36 is provided one or more prongs 39 intended to receive the ear 40 of a clamping handle lever 41 which embraces the operating rod 37. Between the upper end of the pipe 36 and the lever 41, and surrounding the rod 37, is inserted a coiled spring 42 which tends to tilt the clamping lever 41 upwardly and in that manner retain the operating rod 37 in any set position. The upper end of the operating rod 37 carries a ball forming a grip 43 for hand operation and it will now be seen that by pulling or pushing on the grip 43, the opening or closing of the damper door 22 will be effected by hand, through the intermediary of the lever 129 and the rod 37. However, in order to close the damper 22, the clamping handle 41 will have to be depressed to release its hold on the operating

rod 37, but to open the damper door 22, the downward pressure on the grip 43 will be sufficient to compel the clamping handle 41 to yield sufficiently to shift the rod 37 with the lever 129 and damper 22.

Directly inside the adjacent wall of the brooder 10, and secured near the furnace 12, we provide a thermostat 44. This thermostat is furnished for the purpose of automatically regulating the temperature in the brooder and consists of a box 45 at the inner end of which is fulcrumed a lever 46 having its opposite end pivotally connected with an upright bar 47 depending from an arm 147 secured to the operating rod 37. The thermostat further consists of a pair of expandible discs 48 inserted between the bottom of the box and the lever 46 in such a manner that expansion of the discs, due to increasing heat, will compel the lever to rise, carrying with it the bar 47, arm 147, grip 43, operating rod 37 and lever 129, thus closing the damper. An adjusting screw 49 is provided for regulating the amount of expansion of the discs 48.

It will now be understood that the damper 22 can be regulated in either direction manually, by means of the grip 43; that is to say, it can be either opened or closed manually at will. The thermostat is similarly capable of operating the damper 22 in both directions; that is, to close or open the damper, but the clamping handle lever 41 must first be released from the prong 39 as it otherwise will prevent the operation to open the damper. It should be noted that the ball 43 ought to be heavy enough to balance the damper 22 on the lever 129.

A draft pipe 50 has an elbow leading from the ash pit below the grate 17 and the draft pipe extends upwardly above the ground line. The opening 150 in the upper end of the draft pipe may be covered or uncovered by means of a swinging or sliding damper or shutter 51, so as to regulate the amount of air supplied to the furnace. For this purpose, the shutter 51 is suspended in front of the draft pipe opening on a hook 152 from an arm 137. This arm is similar in construction to the arm 147, so as to be lengthwise adjustable by means of a bolt 153 engaging in a slot 154, the arm being made in two parts. Set screws are provided for adjusting the arm 137 in different positions with relation to the rod 37 and hook 152. Similarly, set screws 146 are provided for adjusting the arm 147 on the bar 47 and rod 37.

The flue pipes 27, which commence in the manifold or damper box 23, are embedded in the floor 11 of the brooder and are led in a circuitous manner therethrough to the chimney 52, which extends through the roof of the building, preferably near the wall of the brooder most remote from the furnace. As best seen in Figure 1, at the top of the

chimney 52, we provide a revoluble cap 53 with a weather vane 54.

The chimney 52 is surrounded by a cylindrical ventilator jacket 55 spaced therefrom and retained in position by means of straps 70 56 placed at suitable intervals along the chimney. The opening 57 in the roof, through which the chimney and jacket project, is covered by a flashing plate 58 to prevent leakage, and near the upper end of the 75 chimney is secured a hood 59, the edge of which extends beyond the upper edge of the jacket 55. Close under the roof of the brooder the jacket is formed with an aperture 60 which may be termed a summer ventilator 80 and can be closed by a cap 61. The lower end of the ventilator jacket 55 terminates above the floor of the brooder and damper plates 62 are hinged to the bottom of the ventilator jacket, as at 63, in such manner 85 that they may be opened sideways to regulate the circulation of air.

After fire has been started in the furnace, the cover 16 is laid over the top of the furnace and the shutter 51 of the draft pipe 90 50 is opened to admit air into the fire-box, the damper 22 being simultaneously opened partly or fully, according to the outside temperature at the time. This will compel the heat and smoke from the furnace to pass 95 through the flues 27 into the chimney 52. The temperature of the air in the brooder will now gradually rise through radiation from the chimney as well as from the heated floor 11. As soon as a desired temperature 100 has been attained, the bar 47 of the thermostat is preferably connected to the rod 37 by tightening the set screws 146 of the arm 147, while the clamping handle 41 is released 105 from the prong 39. The cap 61 of the summer ventilator 60 is at this time preferably closed and the damper plates 62 partly opened. This will permit circulation of air 110 in the brooder. Should the temperature rise above a certain amount which is determined 115 by means of the adjusting screw 49, the discs 48 of the thermostat will expand sufficiently to operate the lever 46 and, in this manner, the damper 22 will be closed and no more heat admitted to the flues 27. As 120 the draft through the furnace is in this manner checked the fire will be damped and unless the cover 16 is opened, will eventually die.

When the outside temperature is comparatively high, both the summer ventilator 60 and the damper plates 62 are opened, permitting a perfect circulation of air in the brooder.

In the foregoing description the brooder has been described as having only one series of flues 27 for a small building, but it is evident that a heating system may be provided having two series of flues for a building of comparatively great length. The ar- 125 130 135

angement and construction is similar to the above given description and it is evident that any number of series of flues may be provided from the same furnace to one or more buildings, in accordance with the conditions at hand.

Having thus described the invention, what is claimed as new is:

1. The combination with a heating furnace having a flue extending through a space to be heated, of a manifold having a port for said flue and an opening communicating with said furnace, a damper covering said opening, means for controlling the damper, said means including a lever fulcrumed between its ends and supporting the damper at one end thereof, a manipulating rod hinged at the other end of the lever, a thermostat placed in the space to be heated, and connections between the thermostat and the rod whereby the damper may be automatically operated by the rod and lever in accordance with the temperature in said space.
  2. The combination with a heating furnace having a flue, of a manifold having a port for said flue and an opening communicating with the furnace, a damper covering the opening, means for controlling the damper, said means including a lever fulcrumed between its ends and supporting the damper at one end thereof, a manipulating rod hinged at the other end of the lever, a guide for the rod, a clamping handle for the rod adapted to retain the rod and the damper in adjusted position, said clamping handle having sliding engagement with the manipulating rod, an ear on the handle, a prong on the guide engaging with a corresponding aperture in said ear, a spring between the casing and the handle adapted to tilt the handle with the prong as a fulcrum to firmly grip the manipulating rod.
  3. A flue damper comprising a manifold having a port for the flue and an opening communicating with a source of heat, a

damper covering said opening, means for controlling the damper, said means including a casing on the manifold, a lever pivoted therein supporting the damper at one end thereof, a manipulating rod hinged at the other end of the lever and guided in the casing, and a clamping handle for said rod adapted to retain the rod and the damper in adjusted position, the clamping handle having sliding engagement with the manipulating rod.

4. The combination with a heating furnace having a flue extending through a space to be heated, of a manifold having a port for said flue, and an opening communicating with the furnace, a sliding damper covering said opening, means for controlling the damper, said means including a casing on the manifold, a lever pivoted therein supporting the damper at one end thereof, a manipulating rod hinged at the other end of the lever and guided in the casing, a clamping handle for the rod adapted to retain the rod and the damper in adjusted position, the clamping handle having sliding engagement with the manipulating rod, an ear on the handle, a prong on the casing engaging with a corresponding aperture in said ear, a spring between the casing and the handle adapted to tilt the handle with the prong as a fulcrum to firmly grip the manipulating rod, said furnace having a draft pipe leading to the ash box, a shutter for the pipe, connections between the manipulating rod and the shutter, a thermostat placed in the space to be heated, and connections between the thermostat and the rod whereby the damper may be automatically operated through the intermediary of the rod and the lever in accordance with the temperature in said space.

In testimony whereof we affix our signatures.

JOHN E. MCLEOD. [L. S.]
ARTHUR J. HEWITT. [L. S.]

Certificate of Correction.

It is hereby certified that Letters Patent No. 1,571,854, granted February 2, 1926, upon the application of John E. McLeod and Arthur J. Hewitt, of Washington, Kansas, for an improvement in "Draft Regulators," were erroneously issued to "John E. McLeod and Arthur J. Hewitt," whereas said Letters Patent should have been issued to *John E. McLeod and Arthur J. Hewitt; said Hewitt assignor to Dean W. McLeod, of Washington County, Kansas*, as shown by the records of assignments in this office; and that the said Letters Patent should be read with this correction therein that the same may conform to the record of the case in the Patent Office.

Signed and sealed this 13th day of April, A. D. 1926.

[SEAL.]

M. J. MOORE,
Acting Commissioner of Patents.
